REFRIGERATOR CAR

Gustav P. Torburn, Oakland, Calif., assignor to
Standard Railway Refrigerator Company, a
corporation of Delaware

Application May 25, 1939, Serial No. 275,626

10 Claims. (Cl. 62—17)

This invention relates to refrigerator cars used to transport perishable commodities at a pre-determined temperature. The essential features of such a car are an insulated structure and a refrigerating means for use in warm weather or a heating means for use in cold weather.

The invention relates particularly to refrigerator cars of the overhead bunker type. Cars of this type have the refrigerant container suspended immediately below the roof. They are often provided with drip pans below the containers to form refrigerant compartments below the roof and adjacent the side walls of the car. It is also common to provide means associated with the side walls to form passages for the flow of refrigerated air from the refrigerant compartment to below the floor racks of the car so that it may circulate upwardly through the lading.

It is an object of the invention to form the vertical frame members of the car in tubular form so that they may be utilized for the circulation of refrigerated air from the refrigerant compartment to the lading compartment. It is a further object of the invention to utilize said tubular frame members as a means to dispose of melted or sublimed refrigerant.

Another object of the invention is to provide means for discharging carbon dioxide inside the car or to the atmosphere, according to the preference of the operator. Gaseous carbon dioxide is formed by the sublimation of dry ice.

It is another object of the invention to provide means by which the refrigerant containers are supported partly by the roof and partly by the aforementioned tubular frame members which also serve as conduits for flow of refrigerated air and melted or sublimed refrigerant.

Another object of the invention is to use said tubular frame members as conduits for a heating system. In cold weather, it is necessary during the transportation of some types of commodities, to provide heat to prevent freezing. Under certain other conditions, it is necessary to ventilate the cars. For example, a constant supply of fresh air must be supplied to certain commodities to carry away the heat of respiration and thus prevent undue heating and consequent ripening of fruits. It is a further object of this invention to use said tubular frame members to conduct ventilating air from the refrigerant containers to the space under the floor rack from where it may circulate upwardly to the lading compartment.

It is another object of the invention to facilitate repairs. Removal of the inner lining ex-

poses the tubular frame members and permits easy removal and replacement.

A further object of the invention is to provide a construction of very light weight. The dual use of the tubular frame members as load supporting members and as conduits for the circulation of air and melted or sublimed refrigerant reduces the required number of parts and consequently the weight of the car.

Other objects and advantages of my invention will be apparent from the following detailed description by referring to the drawing which shows the cross section of a refrigerator car embodying my invention.

The frame members of the car shown comprise the metallic tubular member 2 having a horizontal portion 3 and upstanding vertical portions 4. The horizontal portion 3 of the member 2 is associated with other parts of the car, such as, center sill 7, outer side sills 8, lower floor stringers 9, sub-floor 10, fillers 11, inner side sills 12, insulation 13 and decking or floor 14. The floor rack 17 preferably comprises a plurality of spaced apart slats 18 supported above the floor 14 to provide the space 19, thus providing a foraminous member spaced above the floor of the car.

The vertical portions 4 of the member 2 are preferably formed integral with or secured rigidly to the horizontal portion 3 and, being tubular, communicates therewith. The vertical portions 4 are also rigidly secured to the inner side sills 12, lower belt rails 24, upper belt rails 25 and the longitudinal frame members 26. The walls comprise the vertical frame members 4, sheathing 30, insulation 31, lining 32 and side plates 33.

The roof 38 is secured at the eaves to the side plates 33 and has mounted at the ridge a running board 39. The roof 38 is provided with hatches 40 and hatch frames 41 surround the hatches 40 with flanges 42 of the frames overlapping upturned flanges 43 of the roof 38. Refrigerant containers 45 are provided below the roof 38 and adjacent the vertical portions 4 of the tubular members 2. The containers 45 are secured to the hatch frames 41 by the rivets 46 and insulated therefrom by the insulating members 47. The upper ends of the vertical portions 4 of the tubular members 2 communicate with the tanks so that air, liquid or gas, may be drained therefrom. Screens 48 are provided to prevent entrance of solid into the members 2. A ceiling 52 is provided preferably integral with the lining 32 and cooperates with the roof 38 and tubular members 2 to support the containers 45. A tubular brace 55 extends between the adjacent containers 55.

45 and provides communication therebetween. A conduit 56 depending from the brace 55 and communicating therewith provides means by which the circulating air may return from the 5 lading compartment 57 to the refrigerant containers 45.

A depending conduit or drain 65 communicates with the horizontal portion 3 and projects below the floor of the car. A valve 66 is provided in the 10 conduit 65 which valve may be opened to permit the discharge of melted or sublimed refrigerant. A trap 67 is provided to prevent flow of warm 15 air into the car. In transporting certain types of commodities, it is beneficial to have the atmosphere within the car laden with carbon dioxide gas. When dry ice is used as the refrigerant and it is desired to obtain this condition, the valve 66 is closed.

The horizontal portion or drain 3 has apertures 70 distributed throughout its length providing communication between the conduit 3 and the space 19 and the lading compartment 57. Air which is cooled by the refrigerant in the container 45 falls by gravity through the vertical 25 portions 4 into the horizontal portions or conduits 3. Then it escapes through the apertures 70 and is distributed throughout the space 19 and thence through the spaces between the slats 18 to the lading compartment 57. Then the air 30 flows through the conduit 56 and brace 55 to the refrigerant containers where it is cooled again for return to the lading compartment.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

40 I claim:

1. In a refrigerator car having spaced apart walls and a roof extending therebetween, a refrigerant container below said roof and adjacent each wall, a substantially U shaped tubular member having a horizontal portion associated with the floor of said car and a vertical portion associated with each of said walls, each vertical portion communicating at the upper end thereof with one of said containers and said horizontal 45 portion communicating with the lading compartment to form a path for refrigerated air from said containers to the lading compartment, a tubular brace extending between said containers and communicating therewith, said brace having communication with the lading compartment for return of air therefrom to said containers, said member arranged to function as a frame member of said walls and floor.

2. In a refrigerator car body comprising spaced 60 apart walls; a roof; a floor; refrigerant container subjacent said roof; a flue associated with each of said walls, said flues having their upper ends communicating with said container, a horizontal conduit extending between and communicating 65 with said flues, said conduit having apertures therein distributed throughout its length communicating with the lading space above the floor of the car, a drain for said conduit, and means to open or close said drain, whereby cold air from 70 said containers flows through said flues to said conduit and is distributed by said conduit throughout said lading space and whereby melted ice from said container flows through said flues to said conduit and may be temporarily retained 75 therein to cool and humidify said air.

3. In a refrigerator car body comprising spaced apart walls; a roof; a floor; refrigerant container subjacent said roof; a flue associated with each of said walls, said flues having their upper ends communicating with said container, a horizontal 5 conduit below the upper surface of the floor of the car and extending between and communicating with said flues, said conduit having apertures therein distributed throughout its length communicating with the lading space above the 10 floor of the car, a drain for said conduit, and means to open or close said drain, whereby cold air from said containers flows through said flues to said conduit and is distributed by said conduit throughout said lading space and whereby melted 15 ice from said container flows through said flues to said conduit and may be temporarily retained therein to cool and humidify said air.

4. In a refrigerator car body comprising spaced apart walls; a roof; a floor; refrigerant container 20 subjacent said roof; a flue associated with each of said walls, said flues having their upper ends communicating with said container, a horizontal conduit extending between and communicating with said flues, said conduit having apertures 25 therein distributed throughout its length communicating with the lading space above the floor of the car, whereby cold air from said containers flows through said flues to said conduit and may be distributed by said conduit throughout said 30 lading space.

5. In a refrigerator car body comprising spaced apart walls; a roof; a floor; refrigerant container subjacent said roof; a flue associated with each of said walls, said flues having their upper ends 35 communicating with said container, a horizontal conduit below the upper surface of the floor of the car and extending between and communicating with said flues, said conduit having apertures therein distributed throughout its length 40 communicating with the lading space above the floor of the car, whereby cold air from said containers flows through said flues to said conduit and may be distributed by said conduit throughout said lading space, and a foraminous member 45 spaced above said upper surface of the floor of the car.

6. A structure as defined in claim 4 wherein the said flues are formed of metal and rigidly secured to the longitudinal frame members of the 50 car to form a wall framing.

7. A structure as defined in claim 4 wherein the said flues and said conduit are formed of metal and rigidly secured to the longitudinal frame members of the car to form the body framing. 55

8. In a refrigerator car body having spaced apart sills; an insulated floor extending therebetween, a plurality of substantially horizontal metallic conduits extending between said sills and secured thereto to cooperate therewith to form the framing for said insulated floor, said conduits each provided with a plurality of apertures communicating with the lading compartment of the car body above said floor, and means to induce a circulation of cooled air through said conduits 65 which is distributed by said apertures throughout the lading compartment.

9. In a refrigerator car body having spaced apart sills; an insulated floor extending therebetween, a plurality of substantially horizontal 70 metallic conduits extending between said sills and secured thereto to cooperate therewith to form the framing for said insulated floor, said conduits each provided with a plurality of apertures communicating with the lading compartment of 75

the car body above said floor, means to induce a circulation of cooled air and water through said conduits, and valve means to drain said conduits, whereby the air may be distributed by the apertures throughout the lading compartment and the water may be temporarily retained in contact with the circulating air for humidification.

10. A refrigerator car having spaced apart walls; a roof extending therebetween; a refrigerant container below said roof and adjacent each wall, a ceiling below said containers and

extending between said walls, a vertical flue associated with each of said walls with their upper ends communicating with said containers and their lower ends communicating with the lading compartment of the car, a substantially horizontal conduit forming air communication between said containers which also forms a brace therebetween, and a depending conduit providing air communication between the horizontal conduit and the lading compartment of the car. 10

GUSTAV P. TORBURN.
